DESIGN FOR A PAPER FORK.

58,807.

Specification for Design. Patented Aug. 30, 1921.

Application filed January 5, 1920. Serial No. 349,615. Term of patent 14 years.

To all whom it may concern:

Be it known that I, GEORGE P. MALLORY, a citizen of the United States, residing at Yorklyn, in the county of New Castle and State of Delaware, have invented a new, original, and ornamental Design for Paper Forks, of which the following is a specification, reference being had to the accompanying drawing, forming a part thereof.

In the drawings, Figure 1 is a plan view,

Fig. 2 is a side elevation, Fig. 3 is a longitudinal section of a fork embodying my new design, and Figs. 4, 5 and 6 are sections on lines 4—4, 5—5 and 6—6 of Fig. 1, respectively.

What I claim is—

The ornamental design for a paper fork as shown.

GEORGE P. MALLORY.
